United States Patent Office

Des. 209,103
Patented Oct. 31, 1967

209,103

COMBINED MERCHANTISING AND DIS-PENSING CONTAINER

Cornelis Langewis, Walnut Creek, and Henry G. Henrickson, San Leandro, Calif., assignors to Kaiser Aluminum & Chemical Corporation, Oakland, Calif., a corporation of Delaware

Filed July 28, 1965, Ser. No. 86,331

Term of patent 14 years

(Cl. D58—11)

Fig. 1

Fig. 2

Fig. 3

Fig. 4

FIG. 1 is a front elevational view of a combined dispensing and merchandising container, showing our new design;

FIG. 2 is one perspective view thereof;

FIG. 3 is a different perspective view thereof; and
FIG. 4 is an end elevational view thereof.

We claim:

The ornamental design for a combined merchandising and dispensing container, substantially as shown.
